UNITED STATES PATENT OFFICE.

JAFFREY P. BUCHANAN, OF NEWARK, NEW JERSEY.

PORTABLE SURFACE-FINISHER.

1,044,011.

Specification of Letters Patent. Patented Nov. 12, 1912.

Application filed December 20, 1911. Serial No. 666,994.

To all whom it may concern:

Be it known that I, JAFFREY P. BUCHANAN, a subject of the King of Great Britain, and a resident of the city of Newark, county of Essex, and State of New Jersey, have invented certain new and useful Improvements in Portable Surface-Finishers, set forth in the following specification.

This invention relates to portable machine tools and more particularly to tools for removing or polishing surface portions of wooden, metallic and other objects.

One of the purposes thereof is to provide a practical tool of the above character which may be easily transported, expeditiously set up in operative relation to the article to be worked, and which may be accurately adjusted both as to the height of the said article and as to the character of the work to be accomplished.

Further objects of the invention exist in the novel construction and combination of the various parts of the apparatus, illustrative embodiments of which are shown in the accompanying drawings, which form a part of this application, which are particularly described in the following specification, in which like characters designate corresponding parts, and in which,—

Figure 1 is a side elevation of one embodiment of my invention showing the tool carriage in the position it would occupy after having made approximately one-half of a complete cut; Fig. 2 is a plan view of the same illustrating the position of the tool carriage relatively to the transverse frame, after a number of complete cuts and approximately one-half cut more have been made; Fig. 3 is a rear elevation showing parts in the same relative position as in Figs. 1 and 2; Fig. 4 is a fragmentary plan view of a modification of my invention; Fig. 5 is a front elevation of the tool carriage and operating parts; Fig. 6 is a side elevation of the same, and Fig. 7 is a fractional side elevation showing the belt tightening means.

Referring now in detail to the drawings, the apparatus consists essentially of three parts,—a portable base frame A which, in working position, is rigidly secured either directly or indirectly to the work; the transverse frame B which is movably supported and guided with a transverse movement relatively to the work by the frame A; and the tool carriage C movably supported and

guided in the opposite transverse direction by the said traveling frame B.

The base frame A consists of a plurality of frame beams of suitable material, shown as steel angle beams, joined one to another to form a rectangular skeleton structure, two of the opposing parallel angle beams 1 provide parallel tracks or trackways 2, 2 upon which the wheels of the transverse traveling frame B roll. This rectangular frame A is provided with several members 3, (four being illustrated each adjacent the corners), which have sockets formed therein in which leg screws 4 are mounted. Each leg screw 4 is threaded into a tubular leg 5. Suitable means is provided for relatively rotating the leg screws and legs for the purpose of vertically adjusting the mounting of the frame A. This relative rotation may be accomplished in any suitable manner, hand wheels 6 being illustrated for that purpose. Each of the tubular legs 5 is preferably provided with suitable means, shown in the form of a scale for indicating degree of adjustment. In the embodiment shown a narrow slot 7 extends longitudinally of the leg, the margin of which slot is divided off into a scale 8. The finger or pointer 9 is shown loosely associated with the end of each screw 4 and extending out of the slot 7 to cooperate with the scale 8.

Suitable means is provided for rigidly clamping the frame A to the work. In the embodiments illustrated the clamp screws 10 are suitably mounted in the beams 1. Each screw 10 is shown fitted with a hand-wheel 11 to facilitate its manipulation and with a loosely attached flattened piece 12 to abut against the side of the work or work supporting table 13, whereby the same may be clamped rigidly to the frame A. The work being operated upon as illustrated in the drawings is a butcher's chopping block, but it is shown merely for the purpose of illustration, the tool being suitable for operation upon various kinds of work.

In the modification shown in Fig. 4 the clamping screws 10 are shown fitted at their ends with extension blocks 14 suitably shaped in conformity with the cylindrical piece of work therein shown and of a size to adapt the frame to smaller pieces of work than that illustrated in Figs. 1, 2 and 3. It is, of course, to be understood that various extensions of this character suitable for articles of various shapes and sizes are con-

templated. The transverse or traveling frame B is also rectangular in form and of a length corresponding to the width of the base frame A but considerably narrower than the length of the base frame. This frame B is constructed of framed beams 15, 15 and 16, 16 of suitable material and shown as steel angle beams. The two long beams 15, 15 provide a suitable guide-way for the base plate of the tool carriage C for the same to move in a direction at right angles to the movement of the traveling frame B itself. In the embodiment illustrated the vertical flanges of the angle beams serve as confining means for the tool carriage C. Secured in the short sides in the frame B are webs 17 upon which the grooved wheels 18 are rotatably mounted, the grooves of the said wheels being of suitable form to receive the vertical flanges 2-2 of the angle beams 1-1 all of the frame A.

The tool carriage C comprises a base-plate 19 which fits snugly but slidably between parallel flanges of the beams 15, 15 and, supported thereon, is the driving motor 20. Secured to the underside of the base-plate 19 are the bearings 21 within which is journaled the tool shaft 22. Suitable means for driving this tool shaft from the motor 20 is provided. In the embodiment illustrated this means comprises a pulley 23 on the end of the tool shaft 22 driven by the motor 20 through the medium of its pulley 24 and the belt 25. The opposite end of the tool shaft 22 is formed to receive the operating tool 26 which may be a polishing, abrading or cutting tool as illustrated. This tool is shown held in working position by the nut 27.

Upon the lower side of the base-plate 19 and adjacent the rear edge thereof are a plurality of bearing or supporting plugs 28 adapted to rest slidably upon the rear angle beam 15 and to support the rear portion of the tool carriage thereon. Suitable means for adjusting the elevation of the working tool 26 is provided. In the embodiment illustrated this means comprises a pair of adjusting screws 29 threaded through the base-plate 19 along the front edge thereof so that their ends engage the forward angle beam 15. Located between the said screws and secured to the base-plate 19 is a scale member 30. Suitable means is provided for indicating through the medium of the scale member 30 the vertical adjustment of the aforesaid screws 29. This means is shown in the form of pointers 31, one loosely supported by each adjusting screw and relatively, immovable longitudinally thereof. Each pointer is forked at its end so as to straddle the edge of the said scale member 30, whereby the pointer is prevented from turning with the screw 29. A slight but sufficient horizontal adjustment may also be

effected by the screws 29 to incline the base-plate, by screwing one screw 29 lower than the other. This adjustment may be desirable for setting the cutting edge of the tool with greater precision. Means is also shown for the purpose of tightening the driving belt 25. This means comprises a novel mounting for the motor 20. The rear foot or feet of the motor are provided with a half round strip 32 to serve as the bearing upon the base plate 19, while the said feet are held down by the holding down screw 33. Adjusting screws 34 threaded through the base plate 19 engage the front foot 35 of the motor to adjust the same to various elevations, the motor tilting or hinging on the half round strip 32 when the screws 34 are manipulated. The front foot of the motor is held down and set in position by the holding down screw 36.

From the foregoing, the operation of my portable tool will be largely obvious but, as conducing to a clearer understanding thereof, it may here be noted that when it is desired to perform work, such as the squaring up of the surface of a butcher's block, the base frame A is set up surrounding the block and the height thereof adjusted by turning the hand-wheels or other means in the legs. If the trimmed surface is to be true with the floor the indicators on the legs are set at the same height but if the floor is sloping or uneven the legs are then adjusted to render the frame true to the horizontal or to effect any desired angle. The centering screws 10 are then set up, extension blocks being used if necessary, whereby the base frame and work are rigidly held together. The transverse or traveling frame B is then placed on the base frame A and the tool carriage is set in its proper position thereon. The electrical connections having been made to the motor, the traveling frame and tool carriage are moved to and fro over the surface of the block and adjusted by the screws 29 until the cutter 24 just touches the highest point of the block. The traveling frame is then brought back to its limit of travel and the tool carriage moved transversely to its left hand limit. The cutter now being clear of the work the tool carriage is lowered by means of the screws 29 to give the desired depth of cut and this adjustment may be accurately made by noting the position of the indicators 31 upon the scale 30. The motor 120 is now being started and the traveling frame pushed toward the front of the base frame, the cutter travels in a straight line and removes all of the material in its path, to the desired depth. Having finished its cut it is returned to the back of the machine by the operator and the tool carriage is then moved transversely upon the frame B, a distance equal to the width of the cutter. These two operations are then repeated as often as is 130

necessary to traverse the whole surface of the block.

It is to be noted that my apparatus is by no means limited to the use of cutting or planing tools but is also adapted for the operation of a grinding or polishing tool, all denoted generically by the term working tool.

What is claimed and what is desired to be secured by United States Letters Patent is:—

1. In an apparatus of the character described, the combination with a rigid rectangular portable frame adapted to surround a piece of work, said frame having adjustable supports for supporting said frame in a horizontal or an inclined position, and means adjustable relatively to said frame for clamping said frame to said piece of work; of a second frame mounted to travel upon said first frame; a tool carriage slidably mounted upon said second frame; an operating tool carried by said carriage; an electro-motor carried by said carriage; means for adjusting said carriage vertically relatively to said second frame for adjusting said operating tool relatively to said work; power transmission means between said electro-motor and said operating tool; and means operative between said electro-motor and said carriage for adjusting said electro-motor relative to said carriage to adjust said power transmission means.
2. In an apparatus of the character de-

scribed, the combination with a rigid rectangular portable frame adapted to surround pieces of work of various and irregular outlines, said frame being supported upon a plurality of legs, each of said legs being adjustable for coöperating to support said frame in a horizontal or an inclined position, and means adjustable relatively to said frame for clamping said frame to the irregular outline of a piece of work; of a second frame mounted to travel upon said first frame; a tool carriage slidably mounted upon said second frame; an operating tool carried by said carriage; an electro-motor carried by said carriage; adjustable means between said carriage and said second frame whereby said carriage may be inclined relatively to said second frame for adjusting the position of said operating tool relatively to said second frame; power transmission means between said electro-motor and said operating tool; and means operative between said electro-motor and said carriage for adjusting said electro-motor relative to said carriage to adjust said power transmission means.

In witness whereof, I have signed my name to this specification, in the presence of two subscribing witnesses.
